UNITED STATES PATENT OFFICE.

HALBERT H. HOLLOWAY, OF SAN FRANCISCO, CALIFORNIA.

INTAKE-MANIFOLD-HEATING DEVICE.

1,394,830.

Specification of Letters Patent.

Patented Oct. 25, 1921.

Application filed February 25, 1920. Serial No. 361,236.

To all whom it may concern:

Be it known that I, HALBERT H. HOLLOWAY, a citizen of the United States, residing at San Francisco, in the county of San Francisco and State of California, have invented new and useful Improvements in Intake-Manifold-Heating Devices, of which the following is a specification.

This invention relates to a simply constructed, inexpensive device for conducting heat from the exhaust manifold of an internal combustion engine to the intake manifold in such a manner that fuel passing through the manifold will be quickly and effectively heated to the end that a thorough combustion of the fuel and a more efficient engine operation are provided.

An object of the invention is to provide a heating device of the character described which is constructed so that it may be quickly and easily installed for operation and so that the heat is distributed to such portions of the manifold as will most readily and effectively heat the fuel passing therethrough to the engine.

The invention possesses other advantages and features, some of which with the foregoing will be set forth at length in the following description where I shall outline in full that form of the invention which I have selected for illustration in the drawings accompanying and forming a part of the present specification. In said drawings, I have shown one form of the construction of my invention but it is to be understood that I do not limit myself to such form, since the invention as expressed in the claims may be embodied in a plurality of forms.

Figure 1 is a fragmentary side elevation of an internal combustion engine showing the relative positions of the intake and exhaust manifolds and the heating device of my invention.

Fig. 2 is a vertical sectional view taken on the line 2—2 of Fig. 1.

Fig. 3 is a top plan view looking down upon the inside of a modified form of the invention in which the heating element is separate from the intake manifold.

Fig. 4 is a vertical sectional view taken on the line 4—4 of Fig. 3.

Fig. 5 is a fragmentary cross sectional view of a modified form of the invention.

Referring particularly to the drawings, 1 designates the exhaust manifold and 2 the intake manifold of a well known type of

automobile engine and 3 the device of my invention.

My invention contemplates the provision of a novel conductor for conducting heat from the exhaust manifold to the intake manifold. This conductor is constructed so that the heat will be readily conducted to such portions of the intake manifold that the fuel in passing through said manifold will be quickly and effectively heated. One simple, effective, and inexpensive way in which I carry out the invention as illustrated in Figs. 1 and 2 is to provide the heating device as an integral part of the intake manifold. It is obvious that I may make this heating device integral with the exhaust manifold instead of the intake manifold, but I prefer the latter construction, and, as shown, the intake manifold is provided with an integral preferably substantially rectangular upright extension which comprises a solid metal body 4 disposed intermediate of the ends of the manifold and extending from the upper side thereof. This body 4 may be formed when the intake manifold is cast. The inner face of the body 4 adjacent to the outer side thereof is curved as at 5, to conform to the surface contour of the exhaust manifold and closely engage said manifold, as shown in Fig. 2 of the drawings. The upper end of the body is curved inwardly, as at 6, toward the engine and lies upon the upper side of the exhaust manifold so that approximately one half of the surface of said manifold is contacted with by the body 4. The body is thickened from a point approximately central of its ends to the lower end thereof and this thickened portion 7 extends in between the intake and exhaust manifolds. The exhaust manifold is provided with depending spaced ears 8 and these ears are usually bolted to the engine so as to secure the manifold in place. Formed in the thickened portion 7 of the body and spaced from one another are upwardly opening pockets or recesses 9 which receive the ears 8 and are curved and shaped so as to conform to, and engage, said ears.

Thus the heat from the ears 8 is readily transmitted to the upper side of the intake manifold through the lower end of the thickened portion of the body 4 and at points opposite where the lower ends of the ears 8 engage in said body, there are provided relatively hot spots in the manifold. Thus fuel passing upwardly through the mani-

fold, upon coming into contact with these hot portions, will be readily vaporized. This, together with the remainder of the body portion, which acts to transmit heat to the manifold, insures a thorough and effective vaporization of the fuel. By having the heating device formed as a part of the intake manifold, a maximum conduction of heat from the exhaust manifold is provided for. The heating device is constructed so that when the intake manifold is mounted in the ordinary manner upon the engine, the upper portion of the device will engage with the exhaust manifold so as to provide close contact between these parts. I may coat the inner curved face 5 of the body 4 with a heat conducting paste, as shown at 10. This paste is made up largely of metal particles so as to provide for an effective conduction of heat. By interposing a layer of such paste between these surfaces, I provide for a reliable and effective conduction of heat such as would not occur if the surfaces of the body 4 and exhaust manifold were very irregular. By having the body 4 in contact with the upper side of the manifold and extending over and on opposite sides of the point where the vertical portion 2^a of the manifold joins its branches or forks, the liquid particles of the fuel in impinging upon the upper side of the manifold will be readily heated and thoroughly vaporized prior to entering the engine.

Referring to Figs. 3 and 4, the form of the invention shown therein comprises a heating device consisting of a body portion 11 formed of some suitable heat conducting metal. The formation of this body is the same as in the preferred form, except that the body is not formed as a part of either manifold. The body 11 is provided with an inwardly curved upper end 12 corresponding to the end 6 of the preferred form of the invention and is likewise provided with pockets or recesses 13 corresponding to those of the preferred form of the invention. The lower end of the thickened portion 14 of the body is longitudinally grooved, as at 15, so as to closely engage substantially one half of the exposed area of the intake manifold 2. This form of the invention is capable of being mounted in place by forcing the body between the manifolds 1 and 2. The degree of engagement of the body with the manifolds after the body has been forced into place is sufficient to retain the device securely between the manifolds. In both forms of the invention, the body is provided with bolt openings 16 through which bolts 17 that serve to fasten the body and ears 8 of the manifold in place are inserted.

Referring particularly to Fig. 5 of the drawings, the heating device shown is particularly adapted for engines having the in-

take and exhaust manifolds on opposite sides. In this form of the invention, I provide a flat body 18 preferably formed of aluminum. This body extends over the top of the engine and has an enlarged thickened end 19 formed with a curved intake manifold engaging surface 20. The surface 20 rests upon the top of the intake manifold 21. The other end of the body is enlarged as at 22 and provided with pockets 23 for receiving portions of the exhaust manifold 24. This end 22 closely engages the exhaust manifold and conducts heat therefrom to the intake manifold.

I claim:—

1. In combination with the intake and exhaust manifolds of an internal combustion engine, a metal heat conductor arranged between and in contact with each manifold, said exhaust manifold having depending portions and said conductor having pockets therein for reception of said depending portions.

2. In combination with the intake and exhaust manifolds of an internal combustion engine, a metal heat conductor contacting with both manifolds and having an intermediate portion extending between said manifolds.

3. In combination with the intake and exhaust manifolds of an internal combustion engine, a metal heat conductor contacting with both manifolds and having an intermediate portion extending between said manifolds, said conductor having a curved face for engagement with the exhaust manifold.

4. In combination with the intake and exhaust manifolds of an internal combustion engine, a metal heat conductor contacting with both manifolds and having an intermediate portion extending between said manifolds, said conductor having pockets adapted to receive portions of said exhaust manifold.

5. In combination with the intake and exhaust manifolds of an internal combustion engine, of a metal heat conductor having contact with both manifolds, and conducting heat to the upper side of the intake manifold, and means for concentrating the conduction of heat to spaced points on the upper side of said intake manifold.

6. In combination with the intake and exhaust manifolds of an internal combustion engine, a metal heat conductor having engagement with the exhaust manifolds and upper side of the intake manifold.

7. In combination with the intake and exhaust manifolds of an internal combustion engine, of a heat conductor formed integral with, and extending from the upper side of said intake manifold, and contacting with the exhaust manifold.

HALBERT H. HOLLOWAY.
